UNITED STATES PATENT OFFICE

2,454,202

FOLDING PICNIC TABLE

John Pierik, Indianapolis, Ind.

Application June 11, 1945, Serial No. 598,845

1 Claim. (CL. 311—78)

1

The object of my invention is to produce a foldable table structure convenient for transportation and easy erection.

The accompanying drawing illustrates an embodiment of my invention.

In the drawing 10 indicates a main pole to which, at table height from one end, are hinged, at 11, three or more arms 12, 12, 12 swingable either into parallelism with pole 10 or into horizontal positions radiating from pole 10.

Hinged at 13 to each arm 12, is a leg 14 which, when extended, will serve to support its leg in horizontal position. Each arm 12 may conveniently be of channel form so as to permit nesting of leg 14 therein when the arm is swung into parallelism with the pole 10.

In order to hold arms 12, 12, in extended position I provide a locking collar 15 removably sleeved over the upper part of pole 10 and held in arm-bracing position by pin 16 which may be radially removable from pole 10.

Sleevable over the upper end of pole 10 is a fabric table top 17 having a perimeter corresponding to the outline defined by the outer ends of arms 12 when extended. Top 17 at its outer edge is provided with a valance 18 having pockets 19 for the reception of drinking glasses, cutlery, etc. Valance 18 is also provided with grommets 20 adapted, by stretching top 17, to receive pins 21 carried at the outer ends of arms 12, the arrangement being such that top 17, when so tautened, may serve as a support for food, etc.

Post 10 may conveniently be a metal pipe into the upper end of which may be telescoped the stem of a lawn umbrella.

To produce a stable structure there should be at least 3 arms 12 but more may be provided if desired.

I claim as my invention:

A table comprising a central standard having a base, a plurality of arms, hinge means for each of said arms, each hinge means connecting one end of its associated arm to said standard for

swinging movement of the other end of such arm toward and away from said base, each such arm lying substantially parallel with said standard when its said other end is most remote from said base and substantially perpendicular with said standard when its said other end is nearest said base, a leg for each arm, each leg being pivotally connected to its associated arm near said other end of the latter for swinging movement, about an axis substantially parallel with the axis of said hinge means for such arm, each leg being swingable, when its associated arm is substantially perpendicular to said standard, into a position inclined downwardly and outwardly from said standard to support said arm, means slidably mounted on said standard and engageable with the upper surfaces of said arms, when said arms are substantially perpendicular to said standard, to restrain said arms against movement of said other ends thereof away from said base, a top element having a central opening therein sleevable over said standard to overlie said arms and said slidably mounted means, and means for connecting said top element to said arms near said other ends thereof.

JOHN PIERIK.
